US00D955661S

(12) **United States Design Patent** (10) **Patent No.:** **US D955,661 S**
(45) **Date of Patent:** **** Jun. 21, 2022**

(54) **MOUNTING RAIL**

- (71) Applicant: **Gentex Corporation**, Simpson, PA (US)
- (72) Inventors: **Matthew Hanudel**, Dedham, MA (US); **Michael Lawrence Franzino**, Bedford, NH (US); **Stephen Bourque**, Littleton, MA (US); **Scott W. James**, Epping, NH (US); **Daniel Berry**, Rochester, NH (US); **Nathan Winters**, Merrimack, NH (US); **Zoltan S. Brutler**, Groton, MA (US); **Ross Fade Barber**, Auburn, NH (US)
- (73) Assignee: **GENTEX CORPORATION**, Simpson, PA (US)
- (**) Term: **15 Years**
- (21) Appl. No.: **29/783,551**
- (22) Filed: **May 13, 2021**

Related U.S. Application Data

- (63) Continuation of application No. 29/752,259, filed on Sep. 25, 2020, now Pat. No. Des. 922,693, which is a continuation of application No. 29/735,709, filed on May 22, 2020, now Pat. No. Des. 900,407.

(57) **CLAIM**

The ornamental design for a mounting rail, as shown and described.

DESCRIPTION

FIG. 1 is a rear perspective view of a mounting rail showing our new design;

FIG. 2 is a left-side elevational view thereof;

FIG. 3 is a right-side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines illustrate features that form no part of the claimed design.

1 Claim, 7 Drawing Sheets
